S. D. SANDERS.
FENCEPOST,
APPLICATION FILED APR. 14, 1919.

Patented Mar. 23, 1920.

Inventor

S. D. Sanders

By Watson E. Coleman
Attorney

UNITED STATES PATENT OFFICE.

SANFORD D. SANDERS, OF ISLAND CITY, OREGON.

FENCEPOST.

1,334,558.

Specification of Letters Patent.

Patented Mar. 23, 1920.

Application filed April 14, 1919. Serial No. 289,993.

To all whom it may concern:

Be it known that I, SANFORD D. SANDERS, a citizen of the United States, residing at Island City, in the county of Union and 5 State of Oregon, have invented certain new and useful Improvements in Fenceposts, of which the following is a specification, reference being had to the accompanying drawings.

10 This invention relates to certain improvements in fence posts and has relation more particularly to a device of this general character especially designed and adapted for use in connection with barbed wire or the like, and it is an object of the invention to provide a post with novel and improved means whereby the wires may be readily and conveniently secured thereto.

15 The invention consists in the details of construction and in the combination and arrangement of the several parts of my improved fence post whereby certain important advantages are attained and the device rendered simpler, less expensive and otherwise 20 more convenient and advantageous for use, as will be hereinafter more fully set forth.

The novel features of my invention will hereinafter be definitely claimed.

25 30 In order that my invention may be the better understood, I will now proceed to describe the same with reference to the accompanying drawings, wherein:

Figure 1 is a view in elevation, with a portion broken away, of a post constructed in accordance with an embodiment of my invention.

35 Fig. 2 is a fragmentary view partly in side elevation and partly in section of the post as herein disclosed.

40 Fig. 3 is a view in top plan of the post as disclosed in Fig. 1.

Fig. 4 is a fragmentary view in front elevation illustrating a post constructed in accordance with a further embodiment of my 45 invention, and

Fig. 5 is a view taken longitudinally through the post as illustrated in Fig. 4.

As disclosed in the accompanying drawings, P denotes a post which may be formed of any suitable material and which has disposed through its lower end portion the transversely disposed anchoring bars 1 preferably perpendicularly related.

50 55 A face of the post P is provided with a longitudinally disposed groove or channel 2

open at its outer end and said face at opposite sides of the groove or channel 2 is provided with the vertically spaced series of transversely aligned notches 3 in which the 60 wires W of the fence structure are adapted to be received.

Engaged within the groove or channel 2 is a slide S of a length less than the length of the groove or channel 2 and the outer 65 face of said slide S is provided with the notches 4 adapted to register with the transverse notches 3 to also receive the wires W. When the notches 3 and 4 are in register and the wires W positioned therein, the slide S 70 is forced upwardly which results in a crimping of the wires W which results in an effective attachment of said wires W to the post P. This upward movement of the slide S may be effected by inserting a crowbar 75 or the like below the lower end of the slide S.

When it is desired to remove the wires W, it is only necessary to force the slide S downwardly, which may be done by striking with a suitable implement upon the upper end 80 thereof until the notches 3 and 4 are again in alinement.

In the embodiment of my invention as illustrated in Figs. 4 and 5, a slide S' contacts with each pair of transversely aligned 85 notches 3' and said slide S' is capable of limited movement longitudinally of the groove or channel 2' independently of the remaining slides. The slide S' has a notch 4' coacting with the notches 3' for the same 90 purpose hereinbefore referred to relative to the notches 3 and 4.

An end portion of each of the slides S' is provided with an outstanding block 5 which is adapted to be struck or otherwise engaged 95 by a suitable implement to impart the requisite movement to said slide longitudinally of the groove or channel 2' for securing or releasing the wire W.

From the foregoing description, it is 100 thought to be obvious that a fence post constructed in accordance with my invention is particularly well adapted for use by reason of the convenience and facility with which it may be assembled and operated, and it will 105 also be obvious that my invention is susceptible of some change and modification without departing from the principles and spirit thereof and for this reason I do not wish to be understood as limiting myself to the 110 precise arrangement and formation of the several parts herein shown in carrying out

my invention in practice except as herein-after claimed.

I claim:

1. A fence post having a longitudinal groove in one of its faces and having longitudinally spaced notches at opposite sides of the groove, said notches being arranged in pairs with the notches of each pair substantially transversely alined, and slides arranged within the groove, one of said slides coacting with each pair of transversely alined notches, said slides being movable one independently of the other a distance sufficient to remove a strand with which it coacts and each of said slides being provided adjacent an end with an outstanding lug, each of said slides being also provided with a notch for registry with a pair of transversely alined notches of the post with which the slide coacts.
2. A fence post having a groove in one of its faces and having longitudinally spaced notches at opposite sides of the groove said notches being arranged in pairs with the notches of each pair substantially transversely alined, and slides arranged within the groove, each of said slides being pro-

vided with a notch for registry with a pair of transversely alined notches of the post with which the slide coacts, each of said slides being movable independently of the remainder a distance sufficient to remove a strand with which it coacts.

3. A fence post having a groove in one of its faces and having longitudinally spaced notches at opposite sides of the groove, said notches being arranged in pairs with the notches of each pair substantially transversely alined, and slides arranged within the groove, each of said slides being provided with a notch for registry with a pair of transversely alined notches of the post, each of said slides being movable independently of the remainder a distance sufficient to remove a strand with which it coacts, said slides being frictionally held within the groove.

In testimony whereof I hereunto affix my signature in the presence of two witnesses.

SANFORD D. ^{his} X SANDERS.
